UNITED STATES PATENT OFFICE

LYLE C. TILBURY, OF HOUSTON, TEXAS

PIPE HOLDING SLIP

Application filed June 29, 1931. Serial No. 547,637.

This invention relates to a pipe holding slip.

An object of the invention is to provide a slip of the character described shaped to be seated in a downwardly converging seat around a pipe to be held and composed of segments having inside, removable, pipe gripping liners, mounted in the respective segments in a novel manner so that said liners when worn or broken may be readily removed for repairs or replacements.

Another object is to provide a segmental slip having pipe gripping liners on the inner faces of the segments thereof which are secured to the segments in such manner as to withstand the strain to which they may be subjected without breakage of parts and which are so fastened in place that in case of breakage they will not be liable to fall down into the well.

Another object is to provide a slip having novel type handles whereby the slip may be easily handled.

With the above and other objects in view this invention has particular relation to certain novel features of construction, operation and arrangement of parts an example of which is given in this specification and illustrated in the accompanying drawing, where-

in:

Figure 1 shows a plan view of the slip.

Figure 2 shows a vertical sectional view taken on the line 2—2 of Figure 1, and

Figure 3 shows a sectional view taken on the line 3—3 of Figure 2.

Referring now more particularly to the drawing wherein like numerals of reference designate similar parts in each of the figures the numerals 1, 1 and 2 designate the segments of the slip. At their upper ends these segments have the integral, external, arcuate flanges 3, 3 and 4 respectively, having the external, arcuate, grooves, or mortises, 5, 5 and 6, 6 respectively. There are the arcuate hinge plates 7, 7 which are fitted in the respective grooves 5 and whose ends are extended into the grooves 6, said plates being loosely pinned to the flanges 3 by the pins 8, 8 and working on the hinge pins 9, 9 by means of which they are pivoted to the flange 4.

These plates 7 form means for hinging the slip segments together. Fastened to the flange 4 there is a handle 10 and fastened to, and preferably formed integrally with the forward ends of the hinge plates 7, 7 are the handles 11, 11. The handle 10 may be of any selected design to form a convenient grip but the handles 11, 11 are, preferably, loop shaped having relatively long grip portions 12, 12. When the slip is to be seated in position around a pipe the front portions of the loops of the handle 11 may be grasped and held while seating the slip, but when the slip is to be swung open and released from the pipe the slip segments will swing out into approximately straight line relation and when in this position the hands of the workmen may be shifted along the grip portions 12 so as to balance the slip and make it the more easily handled.

The segments have the external, widened, bearing surfaces 13, 13 and 14, which are convex and downwardly tapered to conform to the contour of and to fit into a downwardly converging supporting seat of a rotary table 75 casing head or other support. The segments may be gradually contracted above said bearing surfaces toward the upper ends thereof, as shown in Figure 2 and their lower ends are beveled off as at 15, to facilitate their entry 80 into said supporting seat.

The inner sides of the segments are countersunk providing the upper and lower inwardly extending arcuate retaining flanges 16, 17 and fitted between these retaining flanges are the gripping plates, or liners, 18 whose inner sides are preferably toothed. These liners are arcuate in cross sectional contour to conform to the shape of, and to fit against, the inner sides of the slip segments 85 and to conform to the shape of the pipe to be held, as well.

Each liner 18 has the upper and lower pairs of clamp bolts 19, 19 secured thereto and extending outwardly and arranged substantially parallel and which fit loosely through corresponding bearings 20, 20 through the corresponding segments. The outer ends of these clamp bolts have the clamp nuts 21 screwed thereon and which 100

clamp the liners in place. The bolts 19 are preferably fastened to the liners by inserting and welding their inner ends in suitable bores in the liners provided to receive them.

5 In order to anchor the liners securely in place to take the strain to which they may be subjected they are fitted closely between the corresponding upper and lower flanges 16, 17 and for further anchoring them in 10 place each segment has a relatively large stud 22 which is fitted through and welded in place in a central bearing 23 in such segment and the inner ends of these studs project inwardly and fit snugly in corresponding 15 bearings 24 in said liners 18. These studs 22 and the flanges 16, 17 thus hold the liners firmly in place and relieve the clamp bolts 19 from the strains. The studs 22 are also arranged approximately parallel with 20 the corresponding bolts 19 so that the liners may be readily removed and replaced by direct radial movements thereof, relative to the corresponding segments.

As shown each segment has a central, vertical, relative thin web 25 which merges at 25 its upper end into the upper flange 3, or 4 as the case may be and which merges, at its lower end into the bottom flange 17, and this web 25 is reinforced, on each side with the spaced cross webs 26, 26, for strength. The particular design of the segments may be varied as the circumstances of the case may require. In the form shown the clamp bolts 19, of each pair are arranged on opposite 30 sides of the vertical web of the corresponding segment.

The drawing and description disclose what is now considered to be a preferred form of the invention by way of illustration only 40 while the broad principle of the invention will be defined by the appended claims.

What I claim is:

1. A pipe holding slip shaped to fit in a 45 downwardly converging seat and to surround a pipe, said slip being formed of segments, pipe gripping liners on the inner sides of the segments, upper and lower pairs of clamp bolts secured to the liners and extending through the segments, clamp nuts on the bolts 50 securing them against detachment from the segments.

2. A pipe holding slip shaped to fit in a 55 downwardly converging seat and to surround a pipe, said slip being formed of segments, pipe gripping liners on the inner sides of the segments, upper and lower pairs of clamp bolts secured to the liners and extending through the segments, clamp nuts on the bolts 60 securing them against detachment from the segments, and upper and lower abutments on the segments abutting the corresponding ends of the liners.

3. A pipe holding slip shaped to fit in a 65 downwardly converging seat and to surround a pipe, said slip being formed of segments,

70 pipe gripping liners on the inner sides of the segments, upper and lower pairs of clamp bolts secured to the liners and extending through the segments, clamp nuts on the bolts securing them against detachment from the segments, and reinforcing studs on the segments which project into the liners.

4. A pipe holding slip shaped to fit in a 75 downwardly converging seat and to surround a pipe, said slip being formed of segments, pipe gripping liners on the inner sides of the segments, upper and lower pairs of clamp bolts secured to the liners and extending through the segments, clamp nuts on the bolts 80 securing them against detachment from the segments, upper and lower abutments on the segments against which the corresponding ends of the liners abut and anchors on the segments which project into the liners.

5. A pipe holding slip shaped to fit into a 85 downwardly converging seat and to surround a pipe, said slip being formed of segments, a gripping liner on the inner side of each segment, said liner and its corresponding segment being provided one with approximately 90 parallel clamp bolts and the other with bearings to receive said bolts and clamp nuts on the bolts for securing said liner in place, said segment and liner being also provided one with a reinforcing stud and the other with a 95 bearing into which said stud closely fits.

6. In a pipe holding slip a segment, a gripping liner on the inner side thereof, said segment and liner being provided one with substantially parallel connecting means 100 which project through the other and have clamp means thereon to secure the connected parts together, said segment and liner being provided one with an anchor and the other with a bearing to receive said anchor snugly. 105

7. In a pipe holding slip a segment, a gripping liner on the inner side thereof and detachable therefrom, a bolt on one of said parts 110 and extending through other part, clamp means on the bolt for securing said parts together, said segment and liner being also provided one with a reinforcing stud and the other with a bearing into which the stud closely fits.

In testimony whereof I have signed my 115 name to this specification.

LYLE C. TILBURY.
